(57) **CLAIM**

The ornamental design for a process chamber mixer, as shown and described.

DESCRIPTION

FIG. 1 is a top isometric view of a process chamber mixer, showing our new design.

FIG. 2 is a bottom isometric view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a cross-sectional view taken along line 9-9 in FIG. 7.

FIG. 10 is a cross-sectional view taken along line 10-10 in FIG. 7.

FIG. 11 is a cross-sectional view taken along line 11-11 in FIG. 3.

FIG. 12 is a cross-sectional view taken along line 12-12 in FIG. 3; and,

FIG. 13 is a cross-sectional view taken along line 13-13 in FIG. 3.

The broken lines shown in FIGS. 3 and 7 are included for the purpose of illustrating the boundary and direction of section views and forms no part of the claimed design.

1 Claim, 13 Drawing Sheets
